UNITED STATES PATENT OFFICE.

HENRY DANIEL O'BRIEN, OF FORSYTH, MONTANA.

TRUSS-PAD.

1,185,706.

Specification of Letters Patent.

Patented June 6, 1916.

Application filed May 28, 1915. Serial No. 31,043.

To all whom it may concern:

Be it known that I, HENRY D. O'BRIEN, a citizen of the United States, residing at Forsyth, in the county of Rosebud and State of Montana, have invented a new and useful 5 Truss-Pad, of which the following is a specification.

The device forming the subject matter of this application is a truss, and the invention 10 aims to improve the construction of truss pads so that the same will have the necessary resiliency combined with the necessary rupture sustaining qualities.

It is within the province of the disclosure 15 to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that changes in the precise embodiment of the invention herein disclosed can be made within 25 the scope of what is claimed, without departing from the spirit of the invention.

In the accompanying drawing:—Figure 1 shows in perspective, a truss embodying the 30 present invention; Figs. 2 and 3 are, respectively, longitudinal and transverse sections taken through the front pad; Fig. 4 is a rear elevation showing the front pad detached from the clamping plate.

35 In putting the present invention into practice, there is provided a body-engaging carrying member of any desired form, the same in the present instance being delineated in the form of an arcuate, metal spring 1 carrying at one end, a back pad 2, and at the other end, a front pad 3.

The front pad 3 comprises a supporting plate 4, preferably made of metal and roughly approaching an oval contour. 40 Superposed upon the plate 4 is a hollow body 5 which may consist of one or more layers of rubber, two layers being shown in the present instance. The body 5 is nested within a cushion 6, which may consist of one 45 or more layers of felt, the peripheries of the body and the cushion being in continuous engagement with the supporting plate 4.

Preferably, the body 5 and the cushion 6 are of semi-oval form, as Figs. 2 and 3 will disclose readily. The resilient portion of 55 the pad, comprising the body 5 and the cushion 6, is inclosed in a casing 7 which may comprise one or more layers of oiled silk or other moisture-proof material. The edges 8 of the casing 7 are overlapped upon the 60 rear face of the supporting plate 4 and are united by a stitching 26 running both longitudinally and transversely, thereby to tighten the edges 8 of the casing about the periphery of the supporting plate 4. The 65 stitching 26 may properly be referred to as a lacing cord, since it exercises the function of such an element. The invention comprises a clamping plate 9 having an angularly disposed flange 10 which bears 70 against the edges 8 of the casing 7 to bind the same against the supporting plate 4. Secured to the supporting plate 4 is a threaded stud 11 passing through one end of the spring 1, the stud carrying a nut 12 75 which engages the spring 1.

The construction of the pad 3 is such that it may be taken apart readily, and be detached therefrom with equal facility. Owing to the provision of the resilient body 5 which is nested within the cushion 6, the pad, although affording comfort to the wearer will at the same time be found thoroughly efficient for retaining the rupture. 80 85

Having thus described the invention, what is claimed is:—

In a truss pad, a cushion comprising a plurality of nested cup-shaped elements 90 made of inelastic yieldable material; a body within the cushion and comprising a plurality of nested cup-shaped elements made of resilient material, the innermost cup-shaped element of the body defining an un- 95 encumbered air chamber; each cup-shaped element of the pad being in contact throughout its entire outer surface with the entire inner surface of the next inclosing cup-shaped element thereby to give the pad homogeneity, the cup-shaped elements of the cushion being individually removable, thereby to vary the cushioning effect of the pad, and the cup-shaped elements of the body be- 100

ing individually removable thereby to vary the resiliency of the pad; a supporting plate whereon the edges of all of the cup-shaped elements rest; a covering surrounding the 5 outermost cup-shaped element of the cushion; and means for assembling the covering with the back plate.

Copies of this patent may be obtained for five cents each, by addressing the "Commissioner of Patents, Washington, D. C."

In testimony that I claim the foregoing as my own, I have hereto affixed my signature in the presence of two witnesses.

HENRY DANIEL O'BRIEN.
